M. Wallace, Cincinnati, Ohio, as trustee

Application June 25, 1936, Serial No. 87,200

6 Claims. (Cl. 273—58)

This invention relates to a game and in more particular to a lawn game where balls are rolled over a balk line upon a target having areas of different assigned values.

5 An object of this invention is to provide a game where a player standing back of a foul line rolls or bowls a ball over a balk line upon a target.

Another object of this invention is to provide a target defining the meets and bounds of areas of 10 assigned values without covering said areas.

Another object of this invention is to provide a removably mounted triangular target having divisions therein.

Another object of this invention is to provide a 15 composition for a ball that is easily made, cheap in construction, of proper weight and sufficiently durable to withstand rough usage.

Another object of this invention is to provide a 20 crate for the game.

Other objects and advantages reside in the construction of parts, the combination thereof and the mode of operation, as will become more apparent from the following description.

In the drawings, Fig. 1 discloses a court.

25 Figs. 2 and 3 disclose perspective and exploded views of a crate for the game.

Fig. 4 shows another modification of the target.

The aim of the game is to bowl or roll a ball 10 similar to a bowling ball over a balk line upon 30 a target, the score being dependent upon the location of the ball with respect to various areas in the target.

The players standing to the rear of the foul line 20 roll the ball 10 in the direction of the 35 opposite target 22, the ball rolling over the balk line 24. The foul line 20, the target 22 and the balk line 24 are preferably located on the lawn or on any other suitable grassy lea. The target 22 and the balk line 24 are preferably made from 40 bias tape, the target being staked at each of the three corners of a triangle and the balk line being staked at the ends thereof. The target may be some 15 to 20 yards away from the foul line.

The boundary lines 26 and the partition lines 45 28 are preferably made from bias tape sewed together. The circle 30 may be formed from a suitable annular member, as for example, of fabric. If the ball stops in the circle 30, the player receives the highest score possible. He may, for the 50 purpose of illustration, score 7. If the ball comes to rest in the area designated by the reference character 5, the player scores 5. If the ball alights in the quadrilateral designated by the reference character 4, the player scores 4 and if 55 the ball comes to rest in the area designated by

the reference character 3, the player scores 3 points. It has been found to prove very satisfactory for each player to play two balls from each foul line. For the purpose of identification, the balls of one player differ in color from the other players' balls.

In the modified target shown in Fig. 4, the circle 30 has been omitted. All the scoring areas are either triangular or trapezoidal in shape. This facilitates manufacture. The score values are designated by the numerals found in each area.

BALLS

The balls 10 used in playing this game are preferably four and one-half inches in diameter, each weighing two pounds and ten ounces. The finish is preferably smooth and of such a nature that it will not chip. The balls may be made from various types of material suitable for the use to which they are put.

Composition of core of balls

For the cores 12 of the balls 10 a composition of silica, sulphur and asphalt, having intermixed 25 therein suitable fibrous material, such as cotton or linen rags or jute butts, may be used. This composition is preferably made from finely ground silica and sulphur fused at a temperature of several hundred degrees Fahrenheit in the absence of oxygen. This used silica and sulphur 30 forms a homogeneous mass.

This fused mass is then preferably doused into water so as to congeal the outer surface of the mass; but with the bulk of the mass plastic, that 35 is, the interior of the mass soft. The dousing of the mass solidifying the outer surface prevents oxidation of the sulphur, so that the mass may be handled in air. The silica that has been treated with sulphur will for convenience be referred to as "thermally sulphurized silica," in 40 that the silica is treated with sulphur in the presence of heat.

This sealed bulk of fused silica and sulphur, 45 which may be referred to as thermally sulphurized silica, is then plunged into molten asphalt and after cooling sufficiently, rags, jute butts or other suitable fibrous material is added. The thermally sulphurized silica, molten asphalt and fibrous material are then thoroughly mixed 50 into a uniform constituency throughout.

While plastic this composition may be molded into spheres which form very strong, sturdy cores 55 for the balls. The cores 12 of the balls are molded under the influence of pressure. In order 55

- to produce a smooth outer surface the balls may be doused into cold water, so as to effect the desired surface. This is very essential so as to rapidly set the plastic molding material. As soon as it is set the balls retain their spherical form. The following proportions have been found quite satisfactory: five pounds (5#) of silica with five pounds (5#) of sulphur, to form thermically sulphurized silica having added thereto after being formed twenty pounds (20#) of Trinidad Lake asphalt while in a moulten state, having therein two pounds (2#) of shredded rags or other suitable fibrous material.

15 *Coating process*

As an outer coating 14 for the balls 10 a coating of nitrocellulose material has been found to be very satisfactory. A new process has been developed for applying this nitrocellulose coating 20 to the balls. Any suitable solvent for the nitrocellulose material may be used such as acetone, isetone and the like. Hereafter the generic term "solvent" will be used instead of a specific type 25 of solvent. It is preferable to use the nitrocellulose as thick as possible, as the solvent is comparatively expensive and therefore the cost is affected by the quantity of solvent used. When hardening the nitrocellulose coating it is necessary to withdraw the solvent from the nitrocellulose. The solvent may be withdrawn from the nitrocellulose coating at a comparatively low 30 temperature; but it has a tendency to cause blisters or leave pin holes in the surface of the finished article. In the past, in order to avoid this, it has been customary to freeze the nitrocellulose immediately upon application or to put it into a room where the temperature is extremely low, thereby causing the solvent to slowly leave the coating.

40 In the process used in coating the balls the nitrocellulose dissolved in a solvent is applied by dipping the balls. There is a tendency for the coating to flow downwardly, being attracted by gravity, so as to cause the balls to be lopsided. This has been overcome by revolving the balls 45 in a vertical plane, thereby causing the nitrocellulose coating to be distributed uniformly. Care must be used, however, to control the rate of rotation so as to eliminate undesirable effects of centrifugal force. It has been found that by 50 rotating the balls so as to complete a revolution in a couple of minutes produces very desirable results.

55 As the balls are rotated the balls pass through three zones. It is rather difficult to ascertain without elaborate tests what takes place in each zone. Without definitely knowing what takes place, the following explanation is made as a plausible explanation, with the understanding 60 that the validity and the scope of the patent are not to be influenced by this explanation in the event it is in error. The balls 10 are rotated so as to be dipped into a vat containing a solution which has an attraction for the solvent. Certain 65 petroleum products have such an attraction, as for example, gasoline. For the purpose of illustration, the solvent having an attraction for the nitrocellulose solvent will be referred to as solution, so as to distinguish it from the solvent of the nitrocellulose material. The solution has an 70 attraction for the solvent in which solution the solute, that is, the nitrocellulose material, is insoluble.

75 It has long been known that the solution draws the solvent from the nitrocellulose material—at-

tracts the solvent, so as to withdraw the solvent in a comparatively short time; but if left in the solution for a long period of time the solvent gasifies and forms bubbles within the plastic coating, resulting in the formation of pin holes. It 5 seems that during this process of removing the solvent of the coating material being subjected to the influence of the solution there is a difference in osmotic pressure along the outer surface of the coating and the extreme inner surface thereof. For the convenience of analysis whenever the osmotic pressures throughout the substances are not uniform the rate of increase of the osmotic pressure with distance will be referred to as osmotic pressure gradient. When the nitrocellulose coating 10 is subjected to the influence of the solution over a long period of time, this causes the osmotic pressure gradient to be sufficiently steep or inclined so as to result in the formation of bubbles 15 within the coating, which bubbles are drawn or forced outwardly, due to the difference in osmotic pressures. In so doing, the bubbles leave a void or a small opening, which is generally referred to in the trade as pin hole, which pin hole extends to the outer surface of the coating and 20 leaves a small dimple or depression therein.

It has been found however, that if the balls are submerged in the solution for a short period of time, for a period of time extending over some ten to fifteen seconds, the osmotic pressure 25 gradient may possibly be extremely steep near the outer surface of the coating; but comparatively flat further in. This causes the solvent near the outer surface to pass into the solution, forming a solution therewith; but by removing the 30 balls from the solution within a short period of time the osmotic pressure gradient throughout the entire thickness of the coating is not steep enough to cause the formation of bubbles therein.

35 The balls after leaving the solution are advanced into a zone containing fumes of the solvent. These fumes tend to remove any solution adhering to the surface of the balls. Furthermore, the fumes raise the osmotic pressure 40 at the surface of the ball. While the ball is 45 in the fumes the osmotic pressure gradient throughout the coating of the ball equalizes, that is, the osmotic pressure near the outer surface is increased and the osmotic pressure near the inner surface is lowered, so that the osmotic pressure 50 reaches its own level throughout the entire thickness of the coating.

55 The ball is advanced from the zone of the solvent fumes into the air, where the nitrocellulose material has a slight tendency to dry and the ball may again be advanced into a zone of solvent fumes, back into the solution where the operation 60 is repeated. By the time the ball enters the solution in the succeeding cycle the osmotic pressure gradient throughout the coating of the ball 65 may be substantially uniform, so that as the solution attracts the solvent in the nitrocellulose material the solvent near the outer surface leaves the nitrocellulose material without greatly influencing the osmotic pressure gradient before bubbles form within the coating. The ball is again removed from the solution into the zone containing the fumes of the solvent, from whence 70 the cycle is repeated. It has been found that some thirty to forty cycles, extending over a period of an hour to an hour and fifteen minutes, are sufficient to remove enough solvent from the nitrocellulose coating so as to permit the nitrocellulose coating to be further dried in the open air when the solvent escapes in the form of 75

RULES OF THE GAME

fumes; but not in the form of bubbles. Furthermore, atmospheric moisture has no effect upon the smoothness of the finished surface of the nitrocellulose coating when the coating is in this 5 stage. If the balls were not thus treated, but an attempt were made to dry the balls in the open air immediately after dipping, the moisture in the air would form on the outer surface of the balls in the form of condensation, which 10 condensation causes wrinkling of the outer surface of the nitrocellulose material. By first treating the balls periodically or cyclicly in the solution, followed by a treatment in a zone containing solvent fumes and finally in a zone of air, the 15 nitrocellulose coating becomes immune from deleterious effects of moisture condensation. If pin holes should perchance form in the outer surface of the coating, these may be eliminated by dipping the balls in a very thin nitrocellulose 20 solution which results in an extremely thin coating or film adhering to the outer surface of the coating that has already been applied. Due to the thinness of this second coating the solvent dissolves the outer portion of the first coating so 25 as to permit the nitrocellulose coating to fill the pin holes. This has been found to completely eliminate all traces of pin holes if such pin holes should perchance form in the first coating.

The rate of rotation of the balls is somewhat 30 dependent upon the viscosity of the nitrocellulose material. The rate of rotation, of course, must be changed to accommodate changed conditions in the coating solution.

For some types of work it may be desirable to 35 seal the chamber where the coating is being treated in the several zones, fresh air being supplied as needed and excess fumes being withdrawn, so as to get the proper oxidation of the nitrocellulose coating to properly cure it.

40 HANDLING CRATE

For the convenience of handling the balls which are of a comparatively large diameter on the order of four and one-half inches in diameter or less, a crate has been provided. This 45 crate includes a base member 36 provided with end members 38. The base is provided with recesses 40, one for each ball, so that as the balls are placed in their respective recesses these will not roll out. In order to hold the balls in position a rod 42, which may be either round or 50 rectangular in cross sectional area, supports rubber cups 44, one for each ball, which rubber cups engage the upper surface of the ball when member 42 and the cups 44 are in position, so as to prevent the balls from being displaced even though the crate may be tipped. The rod 42 is held in position by a pin 46 passing through a hole 48 in one end frame 38 and another pin 46 55 slipped into a vertical slot 50, as viewed in Fig. 3, found in the opposite end member 38 and held in position by a hook 52. This crate may be used both as a shipping crate for the balls and as a crate for holding the balls when not in use. The rod 42 in addition to supporting the vacuum cups 44, also serves as a handle for the crate to facilitate the handling thereof.

The game may be played by either two or four players. When played by two, both play from the same end of the court and change ends after all balls have been bowled. Players take turns bowling alternately, the "high point" 5 player of the previous bowl taking first turn. When played by four, the two partners play at opposite ends of the court. Choice of colors of 10 balls may be determined by the players.

The first play of the game is started by bowling the ball to the opposite target. The one 15 nearest the circle 30 has the choice of first or second ball. After the game is started the first player is always the high score man of the last 20 bowl. The players are not permitted to cross the foul line when playing and must cause the balls to cross the balk line in order for the ball to remain in the game. Otherwise, the ball is 25 removed from the court immediately without scoring.

One of the aims of the game is to remove the 30 opponent's ball from scoring position, as the scores are tallied after all the balls have been bowled 25 in a particular frame.

Any suitable score may constitute the game. The scoring positions have already been discussed.

Although the preferred modification of the 35 device has been described, it will be understood that within the purview of this invention various changes may be made in the form, details, proportion and arrangement of parts which generally stated, consist in a device capable of carrying out the objects set forth, in the novel 40 parts, combination of parts and mode of operation as disclosed and defined in the appended claims.

Having thus described my invention, I claim:

1. A game ball consisting of a core of thermally sulphurized silica subsequently intermixed 45 with asphalt molded under pressure while plastic and an outer shell of nitrocellulose material.

2. A game ball including thermally sulphurized silica subsequently intermixed with asphalt 50 molded while plastic into spherical shape.

3. An article including silica and sulphur fused together in the presence of heat to form thermally sulphurized silica and subsequently intermixed with a filler material including a bituminous product.

4. An article including silica fused with sulphur in the presence of heat to form thermally sulphurized silica subsequently intermixed with a bituminous product and fibrous reenforcing 55 material.

5. An article of manufacture including silica fused with sulphur in the presence of heat to form thermically sulphurized silica subsequently intermixed with asphalt having a fibrous filler material therein.

6. An article of manufacture including five parts of silica fused with five parts of sulphur in the presence of heat to form thermically sulphurized silica subsequently intermixed with twenty parts of asphalt.

ELVIN M. BRIGHT.
